UNITED STATES PATENT OFFICE.

LOUIS HINRICHIS, OF NEW YORK, N. Y.

DESIGN FOR A LAMP-SHADE.

SPECIFICATION forming part of Design No. 18,465, dated July 17, 1888.

Application filed April 19, 1888. Serial No. 271,227. Term of patent 7 years.

To all whom it may concern:

Be it known that I, LOUIS HINRICHIS, a citizen of the United States, residing at the city of New York, county and State of New York, 5 have invented and produced a new and original Design for Lamp-Shades, of which the following is a specification, reference being had to the accompanying drawing, forming part thereof.

10 The drawing shows in elevation my newly-designed shade, a single view being deemed sufficient to fully illustrate my design.

15 The leading feature of my design consists in the oblique or diagonal depressed lines or grooves running from the top to the bottom of the body of the shade in two separate directions and crossing each other in the manner shown in the drawing, by means of which the raised diamond-shaped bodies *a a a* and the 20 half-diamond-shaped elevations or bodies *b b b* are formed on the surface of the shade.

25 *A* represents the body of the shade, which may be provided with the outwardly-flaring bell-shaped top *B*, the upper edge of which may be corrugated or fluted, as at *B'*. The

base of the shade is also provided with a rim or flange, *A'*.

30 *C C* represent the depressed lines or grooves which traverse the surface of the shade from the top to the bottom in different directions, one series thereof crossing the other in the manner shown, whereby the raised or diamond-shaped bodies *a a a* and those designated by *b b b* are formed. At the points where the grooves *C C* cross are circular elevations *d d d*, 35 which add materially to the artistic effect.

Having fully described my new and original design in lamp-shades, what I claim, and desire to secure by Letters Patent of the 40 United States, is--

In a design, a lamp-shade having the form and surface configuration herein shown and described.

Signed at the city of New York this 16th day of April, A. D. 1888.

LOUIS HINRICHIS.
